UNITED STATES PATENT OFFICE.

NELSON GOODSELL, OF PHILADELPHIA, PENNSYLVANIA.

DESIGN FOR A SPOON.

SPECIFICATION forming part of Design No. 26,724, dated March 9, 1897.

Application filed December 9, 1896. Serial No. 615,062. Term of patent 3½ years.

To all whom it may concern:

Be it known that I, NELSON GOODSELL, a citizen of the United States, residing at the city of Philadelphia, in the county of Philadelphia and State of Pennsylvania, have invented and produced a new and original Design for Spoons, of which the following is a specification, reference being had to the accompanying drawing, which forms a part thereof.

The accompanying drawing is a plan view of a spoon showing my design, but one view being deemed necessary to fully illustrate the same.

My design consists in a spoon comprising the shape and ornamentation herein shown and described and composed of an elliptical bowl 5, which is concavo-convex in cross-section, from one end of which projects a shank 7, which terminates in the handle 6, the outer end of which is flared or enlarged, as shown at 8, and the extremity of which is elliptical in form and the handle and shank being uniformly tapered from the enlarged end of the handle to the bowl of the spoon.

Midway of the handle is formed or delineated a representation of a stork, as shown at 9, the head and beak of which are directed toward the bowl of the spoon and the wings 30 being extended outwardly along the edges of the handle in the direction of the outer end thereof, as shown at 10, and mounted astride of the stork is the figure of a child, as shown

at 11, one hand being directed downwardly so as to rest on the neck of the stork, while 35 the other hand is raised and grasps the shaft or cross-bar of a banner, as shown at 12.

That portion of the handle on each side of the banner and along the edges of the handle is ornamented, as shown at 13, by the representation of feathers, which are entwined or intertwined to form convolutions, and formed or disposed upon the shank between the head of the stork and the bowl of the spoon is an ornamented configuration, as shown at 14, 45 and at the junction of the shank and the bowl and upon the edges of the latter are other ornamentations, as shown at 16, the shank 15 being plain or without ornamentation.

My new and original design is symmetrical and attractive in form, and,

Having fully described the same, what I claim, and desire to secure by Letters Patent, is—

The design for a spoon herein shown and described.

In testimony that I claim the foregoing as my invention I have signed my name, in presence of the subscribing witnesses, this 5th day of December, 1896.

NELSON GOODSELL.
